2 Sheets-Sheet 2

Fig. 2. A side cross-sectional view of a device assembly. It features a vertical tube 18 with a flared base 21. A central tube 7 is inserted into tube 18. A flange 11 is attached to the top of tube 7. A retaining ring 12 is positioned on tube 7 just below flange 11. A retaining ring 19 is located on tube 7 just above flange 11. A retaining ring 10 is at the bottom of tube 7. A retaining ring 15 is at the top of tube 18. A retaining ring 17 is at the bottom of tube 18. A retaining ring 14 is at the top of tube 18. A retaining ring 20 is at the bottom of tube 7. A retaining ring 8 is at the top of tube 7. A retaining ring 3 is at the bottom of tube 7. A retaining ring 13 is at the top of tube 18. A retaining ring 21 is at the bottom of tube 18. A retaining ring 2 is at the top of tube 18. A retaining ring 1 is at the bottom of tube 18.

Fig. 4. A side cross-sectional view of a device assembly. It features a vertical tube 24 with a flared base 23. A central tube 2 is inserted into tube 24. A flange 30 is attached to the top of tube 2. A retaining ring 31 is positioned on tube 2 just below flange 30. A retaining ring 32 is located on tube 2 just above flange 30. A retaining ring 33 is at the bottom of tube 2. A retaining ring 34 is at the top of tube 2. A retaining ring 35 is at the bottom of tube 24. A retaining ring 36 is at the top of tube 24. A retaining ring 25 is at the bottom of tube 24. A retaining ring 22 is at the top of tube 24. A retaining ring 5 is at the bottom of tube 24. A retaining ring 28 is at the top of tube 24. A retaining ring 27 is at the bottom of tube 24. A retaining ring 37 is at the top of tube 2.

Fig. 5. A top-down view of a circular component. It features a central square 29. A retaining ring 31 is positioned around the square 29. A retaining ring 32 is located at the bottom of the component. A retaining ring 33 is at the top of the component. A retaining ring 28 is at the bottom of the component. A retaining ring 25 is at the top of the component. A retaining ring 1 is at the bottom of the component.

UNITED STATES PATENT OFFICE

JOHN ORAWIEC, OF CHICAGO, ILLINOIS

WRENCH

Application filed January 19, 1931. Serial No. 509,830.

The present invention relates generally to wrenches and more particularly to new and useful improvements in a device or tool of this character which is in the nature of a speed wrench and has for its primary object to provide, in a manner as hereinafter set forth, a wrench embodying a spirally twisted rotatable bar having mounted for reciprocation thereon a manually operable actuating sleeve for the bar. The invention further includes means for selectively causing rotation of the bar in either direction when the actuating sleeve is reciprocated thereon.

Another important object of the invention is to provide a wrench of the character described embodying novel means for expeditiously adjusting the tool in a manner to cause the bar to be rotated in either direction upon reciprocation of the actuating sleeve thereon.

Still another important object of the invention is to provide a wrench of the character set forth embodying a spirally twisted rotatable bar having mounted for rotation on one end portion thereof a novel construction of head. The invention further contemplates means for permitting rotation of the bar independently of the head selectively in one direction but wherein the head and the bar will be locked together should said head be rotated in the opposite direction.

Other objects and advantages of the invention are to provide a wrench of the aforementioned character which will be simple in construction, strong, durable, efficient and reliable in use and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in elevation of a wrench constructed in accordance with this invention.

Figure 2 is a detail view in vertical section through the actuating sleeve.

Figure 3 is a horizontal cross sectional

view taken substantially on the line 3-3 of Figure 2 looking upwardly, and indicated by the arrows.

Figure 4 is a detail view in vertical section taken substantially on the line 4-4 of Figure 1 through the upper end portion of the tool.

Figure 5 is a horizontal sectional view taken substantially on the line 5-5 of Figure 4 looking upwardly as indicated by the arrows.

Figure 6 is a detail view in elevation showing the pawl shifting means.

Figure 7 is a detail view in elevation showing the means for locking the head to the rotatable bar.

Referring to the drawings in detail, it will be seen that the reference numeral 1 designates generally an elongated bar having the oppositely twisted upper and lower spiral portions 2 and 3, respectively, which merge with each other at the longitudinal center of the bar 1, as at 4, and which terminate at their free ends in the end portions 5 and 6, respectively of polygonal horizontal cross section.

A substantially cylindrical sleeve 7 is mounted for reciprocation on the bar 1 and is spaced concentrically with respect thereto, the sleeve 7 being provided with a longitudinal slot 8 in its upper portion, the purpose of which will be more fully hereinafter set forth. Rings 9 and 10 are mounted in the end portions of the sleeve 7, bearing balls 11 being interposed between said rings and the sleeve. The inner ends of the rings 9 and 10 have formed thereon the teeth 12 and formed integrally with the outer end portions of the rings are the internal flanges 13 having an inner periphery of a configuration conforming substantially to the spiral portions 2 and 3 of the bar 1 for operatively connecting the rings 9 and 10 to said bar 1.

Pivotedly mounted in the upper and lower portions of the sleeve 7 adjacent the rings 9 and 10 is a pair of rockable, double ended pawls 14 and 15 which, as illustrated to advantage in Figure 6 of the drawings, are oppositely disposed with respect to each other. In opposite sides the pawls 14 and 15 are pro-

vided with notches 16 for the reception of the arcuate spring fingers 17 which are mounted on the upper and lower ends of a bar or rod 18 which is mounted for reciprocation in the sleeve 7. At its upper end the rod 18 is provided with an extension 19 which is operable in the slot 8 and has fixed on its outer end a suitable head or button 20 for engagement by the finger of an operator of the tool for shifting the rod 18 longitudinally in the sleeve 7. The lower portion of the rod 18 is slidable through a notch in an annular guide 21 which is provided therefor in the lower portion of the sleeve 7, the guide 21 being fixed in the sleeve 7 and encircling the bar 1.

Referring now to Figures 4 and 5 of the drawings, it will be seen that a bushing 22 is mounted on the polygonal upper portion 5 of the bar 1 for rotation therewith and said bushing includes a reduced depending portion 23 upon which is rotatably mounted a knurled sleeve 24 having fixed on its upper end portion a flat annulus 25 which is disposed beneath and against the main body portion of the bushing 22. The reference numeral 26 designates a head provided with a transverse opening through which is disposed a bar 27, said bar 27 being adjustable in the head 26. The head 26 includes an integral depending skirt portion 28 which rotatably encircles the bushing 22 and extends below the main body portion of said bushing 22, as clearly seen in Figure 4 of the drawings. The skirt 28 is provided with teeth 29 on its inner periphery. The portion of the skirt 28 which extends below the main body portion of the bushing 22 has mounted therein an anti-friction bearing 30 which is cooperable with a substantially conical upper portion of the sleeve 24.

Referring now to Figure 5 of the drawings, it will be seen that the periphery of the bushing 22 is provided with a notch or recess 31 the inner wall of which is of a configuration to provide a fulcrum point 32. A pawl 33 is operable in the notch or recess 31 and is rockable on the fulcrum point 32 for engaging either end of the pawl 33 with the teeth 29 in the skirt 28. The pawl 33 rests on the annulus 25 and is shiftable through the medium of an upstanding finger 34 which is disposed on the annulus 25.

A socket member 35 is rotatably mounted on the anti-friction bearing 36 in the upper portion of the bore of the bushing 22, said socket member 35 extending upwardly into an opening provided therefor in the head 26 which communicates with the transverse opening in which the bar 27 is mounted. A spring pressed detent 37 is mounted in the socket member 35 for engagement in a recess provided therefor in an intermediate portion of the bar 27 for releasably securing said bar 27 in position on the head 26. The reference numeral 38 designates the coil spring which

actuates the detent 37, said coil spring being disposed in the socket member 35 and having one end engaged with the bottom of said socket member and its other end engaged with the detent 37 in a manner to yieldably urge said detent into engagement with the bar 27.

A bifurcated block 39 is fixed on the lower end portion 6 of the bar 1 and has mounted for swinging movement between the arms or furcations 40 thereof a head 41. The head 41 is provided with an apertured ear 42 which is disposed between the arms or furcations 40 and is pivotally connected thereto by a suitable pin 43. Any suitable means may be provided for detachably fixing the block 39 to the lower end portion 6 of the bar 1.

In use, when the rod 18 is shifted in one direction the pawls 14 and 15 are rocked to engage the teeth 12 on the rings 9 and 10 in a manner to lock said rings to the sleeve 7 against rotation in opposite directions. In other words, when the ring 10 is locked to the sleeve 7 by the pawl 15, the pawl 14 will ride over the teeth 12 on the ring 9 and permit rotation of said ring 9 independently of the sleeve 7. Thus it will be seen that upon downward movement of the sleeve 7 the ring 10 will be locked thereto and rotary motion will be given to the bar 1 by reason of the operative engagement of the ring 10 with the portion 3 of said bar 1. The ring 9 being operatively connected to the oppositely spiralled portion 2 of the bar 1 will be rotated independently of the sleeve 7. Upon upward movement of the sleeve 7 the ring 9 will be locked to the sleeve 7 by the pawl 14 and said ring 9 being operatively engaged with the spiral portion 2 of the bar 1, will rotate said bar 1 in the same direction, the ring 10 rotating independently of the sleeve 7 during the upward movement of said sleeve 7. Should it be desired to reverse the direction of rotation of the bar 1, it is only necessary to shift the rod 18 and thus rock the pawls 14 and 15 as indicated in broken lines in Figure 6 of the drawings. It will be noted that the pawls 14 and 15 are rocked simultaneously in opposite directions due to the arrangement of the spring fingers 17. During the aforementioned operation the head 26 is rotatable on the bar 1 but should it be desired to lock the head 26 to the bar 1 for using the bar 27 as a lever for tightening or loosening a nut, it is only necessary to rotate the ring 24 in a manner to shift the pawl 33 to the desired position for engagement with the teeth 29 and in this manner the head 26 is locked to the bar 1 through the medium of the bushing 22. The bar 27 may then be used to rotate the bar 1. If desired, the head 41 may be swung to a position substantially at right angles to the bar 1 and said bar 1 then used as a lever to tighten or loosen a nut. The pawls 14 and 15 are, of course, curved longitudinally

to conform to the curvature of the sleeve 7, as illustrated to advantage in Figure 3 of the drawings.

It is believed that the many advantages of a wrench in accordance with this invention will be readily understood, and although the preferred embodiment of the invention is as illustrated and described, it is to be understood that changes in the details of construction may be had which will fall within the scope of the invention as claimed.

What is claimed is:—

1. A wrench comprising an elongated bar including oppositely spiralled portions, nut 15 engaging means on one end of the bar, an elongated sleeve mounted for reciprocation on the bar, means in the sleeve for operatively connecting the bar thereto for rotating said bar in a selective direction upon reciprocation 20 of the sleeve the second named means comprising rings mounted for rotation in the end portions of the sleeve and operatively engaged with the oppositely spiralled portions of the bar, teeth on the rings, and oppositely disposed double ended rockable pawls 25 pivotally mounted in the sleeve and operatively engageable with the teeth in a manner to lock the rings to the sleeve against rotation independently of said sleeve in opposite directions.

2. A wrench comprising an elongated bar including oppositely spiralled portions, nut 30 engaging means on one end of the bar, an elongated sleeve mounted for reciprocation on the bar, means in the sleeve for operatively connecting the bar thereto for rotating said bar in a selective direction upon reciprocation of the sleeve, the second named means comprising rings mounted for rotation 35 in the end portions of the sleeve and operatively engaged with the oppositely spiralled portions of the bar, teeth on the rings, oppositely disposed double ended rockable pawls 40 pivotally mounted in the sleeve and operatively engageable with the teeth in a manner to lock the rings to the sleeve against rotation independently of said sleeve in opposite directions, and manually operable means for shifting the pawls in a manner to reverse 45 50 the direction of rotation of the bar upon reciprocation of the sleeve thereon.

3. A wrench comprising an elongated bar including oppositely spiralled portions, nut 55 engaging means on one end of the bar, an elongated, substantially cylindrical sleeve mounted for reciprocation on the bar, means in the sleeve for operatively connecting the bar thereto for rotating said bar in a selective direction upon reciprocation of the sleeve, 60 the second named means comprising rings mounted for rotation in the end portions of the sleeve and operatively engaged with the oppositely spiralled portions of the bar, teeth on the inner ends of the rings, oppositely 65 disposed double ended rockable pawls piv-

otally mounted in the sleeve and operatively engageable with the teeth in a manner to lock the rings to the sleeve against rotation independently of said sleeve in opposite directions, and manually operable means for shifting the pawls in a manner to reverse the direction of rotation of the bar upon reciprocation of the sleeve thereon, the last named means comprising a rod mounted for reciprocation in the sleeve, resilient fingers mounted on the end portions of the rod and operatively connected with relatively opposite end portions of the pawls.

In testimony whereof I affix my signature.
JOHN ORAWIEC.
